DESIGN FOR A STOVE by William B. Gleason

Assigned to James Hartshorn and Winslow Ames.

Patented 26. November 1850.

Des. 337

Wm B. Gleason of Boston Mass. Assignor to
Hartshorn & Ames of Nashua N. H.
Letters Patent. No. 337. Dated Nov. 26. 1850.

The Schedule referred to in these Letters Patent making part of the same.

To all Persons to whom these Presents shall come:

Be it known
that I, William B. Gleason, of Boston, in the County of Suffolk and State of Massachusetts, have invented or produced a new and useful ornamental design or configuration for a stove; and I do hereby declare the same to be represented and described in the following specification, and accompanying drawing, letters, figures, and references thereto.

The said drawing consists of a Back view of a Stove my design being applicable to each side, or the back, or front of the stove.

It consists of a star a, a surrounding fillet c, a system of rays b, and six circular torus arcs d, e, f, g, h, i, and two straight connecting toruses k, l, all combined together, and formed in bas, or alto relief, as represented in the drawing. The said design may be surrounded by mouldings in relief, or incavo, or both as circumstances may require, and it may be applied to any part of the stove, where it is convenient to place it, for the purpose of ornament.

I claim the ornamental design or combination of the star a, the fillet c, the system of rays b, the six torus arcs d, e, f, g, h, i, and two straight connecting toruses k, l, as disposed essentially as specified.

In testimony whereof I have hereto set my signature,
this eleventh day of October A. D. 1850.
